UNITED STATES PATENT OFFICE.

GEORGE W. HOUSEL, OF BLOOMSBURY, NEW JERSEY.

RAILWAY-TRAIN TIMER.

SPECIFICATION forming part of Letters Patent No. 375,160, dated December 20, 1887.

Application filed October 26, 1886. Serial No. 217,229. (No model.)

To all whom it may concern:

Be it known that I, GEORGE W. HOUSEL, of Bloomsbury, in the county of Hunterdon and State of New Jersey, have invented a new and Improved Train-Timer, of which the following is a specification, reference being had to the annexed drawings, forming a part thereof, in which—

Figure 1 is a front elevation of my improved train-timer. Fig. 2 is a rear elevation of the same. Fig. 3 is a vertical transverse section taken on line xx in Fig. 1. Fig. 4 is a plan view, and Figs. 5, 6, and 7 are detail views, of parts of the circuit-breaking devices.

Similar letters of reference indicate corresponding parts in all the views.

My invention is designed to indicate to engineers or train-men running trains over a section of road the time when the last train passed the indicator, as well as the time of day, so that the engineer may know by a glance at the instrument the exact interval of time between his train and the one preceding him.

My invention consists in a clock-movement provided with a series of concentric arbors for carrying two pairs of hands, one pair being operated by the time-movement in the usual way, the other pair being arranged to be moved at intervals by a suitable spring-motor, its movement being controlled by a galvanic battery, a circuit-closer connected with the railroad-track, a circuit maker and breaker connected with the clock-movement, and a magnet placed in the battery-circuit and arranged to be operated by the circuit-breaker connected with the track and by the circuit maker and breaker connected with the clock-movement, the circuits, the magnet, and the circuit making and breaking devices being arranged relative to each other, so that the momentary closing of the circuit by a passing train will energize the magnet and release the motor carrying the auxiliary indicating-hands, when the circuit, through the magnet and battery, will be completed by the circuit maker and breaker connected with the movement, and will remain in that condition until the auxiliary hands occupy a position coincident with the time-hands, all as hereinafter more fully described.

The clock-movement A is of the usual description, having the spring B, the first wheel,

C, and the usual train of gearing terminating with the scape-wheel D and driving the tubular minute-hand arbor E. The said minute-hand arbor communicates motion to the hour-hand sleeve F through the pinion a , secured to the minute-hand arbor, the wheel b , turning on the stud c , the pinion d , carried by the wheel b , and the spur-wheel e , secured to the hour-hand sleeve F.

In the tubular arbor E is placed a tubular arbor, G, which contains the arbor H. The arbors G H project beyond the front and rear of the time-movement. In the opposite side of the clock-frame is arranged a train of motor-gearing, I, driven by the spring-actuated wheel J and terminating in the fly-fan arbor K. To the second arbor, L, of the motor-gearing, upon the end of the arbor projecting through the rear plate of the movement, is secured a spur-wheel, f , which engages a pinion, g , turning on the stud h , projecting from the rear plate of the movement. To the pinion g is secured a spur-wheel, i . The pinion g meshes into a spur-wheel, j , secured to the tubular arbor G, which carries a hand, k , corresponding to the hour-hand of the time-movement, and the spur-wheel i meshes into the pinion l , secured to the arbor H, the said arbor carrying a hand, m , corresponding to the minute-hand of the time-movement. The gearing for imparting motion to the arbors G H and hands k m , carried thereby, is so proportioned as to cause the hand m to make twelve revolutions while the hand k is making one revolution, the relation of the speeds of the two hands being the same as that of the minute and hour hands of the clock.

The sleeve F carries an hour-hand, k' , and the tubular arbor E carries a minute-hand, m' , and between the hour-hand k' on the sleeve F and the wheel e , secured to the said sleeve, is loosely placed a spur-wheel, n , of vulcanite or other insulating material.

In an annular groove in the outer face of the wheel n is placed a metallic ring, o , from which a stud, p , projects through the wheel and beyond its inner face into contact with the wheel e . The outer face of the vulcanite wheel n is shown in Fig. 6, and its inner face is shown in Fig. 7. In the face of the wheel e and in the path of the stud p is placed an in-

ulating-bar, *q*, which is held in its place in the face of wheel *e* in the present case by a vulcanite ring, *r*, formed integrally with the bar and surrounding the periphery of the plain part of the wheel. The spur-wheel *n* is made to revolve with the hour-hand *k* on the arbor *G* by motion imparted to it from the spur-wheel *j* on the rear end of the arbor, through the wheel *s*, engaged by the wheel *j*, the arbor *t*, carrying the said wheel, and the spur-wheel *u*, meshing into the vulcanite ring *n*.

In the portion of the movement which contains the motor gearing is journaled a rock-shaft, *v*, in insulating-bearings *w* in the plates of the movement. The forward end of the rock-shaft *v* carries a metallic arm, *M*, which reaches down over the outer face of the spur-wheel *n*. To the rock shaft *v*, between the plates of the movement, is secured an arm, *a'*, which extends upward to the fly-fan *b'* on the arbor *K*, and which may be moved into and out of the path of the fan. The fly-fan is provided with insulating-plates *c'* for preventing the passage of the current through the fan. Behind the movement *A* is supported an electro-magnet, *N*, having an armature, *O*, which is connected by a spring, *d'*, with the standard *e'*.

To the rear end of the rock-shaft *v* is secured an arm, *f'*, which is bent twice at right angles and extends down to the armature *O*, the extremity of the right-angled arm being received under the finger *g'*, attached to the armature and extending over the top thereof parallel with its upper surface, so that when the armature *O* is moved the arm *f'* will also be moved.

To the base *P* of the instrument there are secured binding-posts 1 2 3 4. The binding-posts 1 2 are connected electrically with the terminals of the electro-magnet *N* by wires *h' i'*. One terminal of the electro-magnet is connected with the binding-post 4 by the wire *j'*, and the other is connected with the frame of the clock-movement by the wire *l'*. The binding-post 3 is connected with the armature-standard *e'* by the wire *o'*. The binding-posts 3 4 are connected with the poles of the battery, and the binding-posts 1 2 are connected with the circuit-closer attached to the railroad-track.

When a train passes over the circuit-closing track-instrument, the magnet *N* is energized, and its armature *O* is drawn down, thereby turning the rock-shaft *v*, swinging the arm *a'*, so as to release the fly *b'*, allowing the motor movement to revolve, and through its shaft *L* and the spur-wheels connected therewith to impart rotary motion to the arbors *G H* and hands *k m*, carried thereby, and at the same time to impart motion to the vulcanite spur-wheel *n*, causing it to carry the stud *p* around on the face of the wheel *e* and bringing the free end of the arm *M* into contact with the metallic ring *o*, whereby the circuit is completed through the wire *o'*, the armature-standard *e'*, armature *O*, arm *f'*, rock-shaft *v*, arm *M*, metallic ring *o*, stud *p*, wheel

e, the frame of the clock-movement, the wire *l'*, magnet *N*, and the wire *j'*.

The insulating-bar *q* in the face of the wheel *e* corresponds in position with the hour-hand *k* on the sleeve *F*, and the stud *p*, carried by the wheel *n*, corresponds in position with the hour-hand *k* on the tubular arbor *G*. So long as the electric circuit is maintained by the contact of the stud *p* with the metallic part of the wheel *e* the armature will be held down upon the magnet *N* and the hands *k m* will continue to move forward; but when the stud *p* reaches the insulating-bar *q*, carried by the wheel *e*, the circuit is broken, the armature *O* is released, and is raised by its spring-support, turning the rock-shaft *v* and carrying the arm *a'* into the path of the fly-fan *b'*, stopping the motor movement, at the same time removing the end of the arm *M* from the metallic ring *o* in the face of the wheel *n*. This stoppage of the motor movement will occur only when the hands *k m* connected therewith coincide in position with the hands *k' m'*, connected with the time-movement. The hands *k m* will remain in this position while the hands *k' m'*, connected with the time-movement, continue to revolve at their regular rate.

When the hands of the instrument are observed, the difference between the time indicated by the time-hands and that indicated by the hands carried by the motor will show the time that has elapsed since the circuit was closed by the passing of a train over the circuit-closing track-instrument.

The clock is to be provided with a glass dial, so that the position of the hands may be observed at night, when a lamp is placed behind the dial.

Having thus fully described my invention, I claim as new and desire to secure by Letters Patent—

1. In a train-timer, the combination, with the time-marking hands of a clock and the movement connected therewith, of a pair of auxiliary hands arranged on an axis coincident with that of the clock-hands, an auxiliary spring and gearing for driving the two auxiliary hands at different speeds bearing the same relation to each other as the speed of the hour and minute hands of the time-movement, and means for stopping and starting the auxiliary hands, substantially as specified.

2. In a train-timer, the combination, with a clock-movement and time-indicating hands carried thereby, of an auxiliary pair of hands having independent driving mechanism, and an electro-magnetic circuit-controller, and stop mechanism for arresting the motion of the auxiliary hands when their position coincides with the position of the time-indicating hands, substantially as specified.

3. In a train-timer, the combination, with the clock-movement *A*, provided with the tubular arbor *E*, carrying the minute-hand *m'*, and the wheel *e* and sleeve *F*, carrying the hour-hand *k'*, of the insulating-bar *q*, carried

by the wheel e , the insulating-wheel n , provided with the metallic ring o and stud p , and mounted loosely on the sleeve F , the rock-shaft v , mounted in insulating-supports, the 5 arm M , carried by the said rock-shaft and contacting with the face of the wheel n , the arm f' , attached to the rock-shaft v , the electro-magnet N , armature O , connected with the arm f' , means for turning the insulating-wheel n , and 10 the electric-circuit connections, substantially as specified.

4. In a train-timer, the combination, with the clock-movement A , provided with the tubular arbor E , carrying the minute-hand m' , 15 and the wheel e and sleeve F , carrying the hour-hand k' , of the tubular arbor G , inserted in the arbor E , the arbor H , contained by the tubular arbor G , the hands $k\ m$, carried by the arbors $G\ H$, the spring-actuated motor I , connected with the arbors $G\ H$, and means for 20 starting and stopping the motor I , substantially as specified.

5. In a train-timer, the combination, with

the clock-movement A , provided with the tubular arbor E , carrying the minute-hand m' 25 and the wheel e , and sleeve F , mounted loosely on the arbor E and carrying the hour-hand k' , of the tubular arbor G , inserted in the arbor E , the arbor H , contained by the tubular arbor G , the hands $k\ m$, carried by the arbors $G\ H$, the spring-actuated motor I , connected with the arbors $G\ H$, the insulating-bar q , carried by the wheel e , the insulating-wheel n , provided with the metallic ring o and stud p , the wheels $s\ u$, and arbor t , for imparting motion from the arbor G to the wheel n , the insulated rock-shaft v , the arm M , carried by the said rock-shaft and bearing on the face of the wheel n , the arm f' , attached to the shaft v , the electro-magnet N , the armature O , connected with the arm f' , and the current-connections, substantially as specified. 30 40
